COLLAPSIBLE ICE BUNKER

Gustav P. Torburn, Oakland, Calif., assignor of
one-half to Loyd E. Cartmill, Palo Alto, Calif.

Application Apr. 2, 1938, Serial No. 199,650

15 Claims.

(Cl. 62—19)

The present invention relates to refrigerator cars, and more particularly to collapsible ice bunkers therefor, which permit the car to be used either for standard refrigeration service with the ice contained in bunkers at the ends of the car, or for so-called top icing service, in which chipped or cracked ice is placed among and on top of the lading, or for non-refrigerated freight service. In either of the two latter services, the ice bunkers are collapsed or folded in such a manner that the entire interior of the car can be used for lading.

The principal object of the invention is to provide a collapsible ice bunker whose walls, when collapsed, are flush with and form extensions of, the lining of the car, to prevent waste of space and to facilitate loading. Another object is to use portions of the bunker lining as locked ventilating gates under the ice hatches, to prevent pilfering of the lading through said hatches when the bunker is collapsed. Another object is to provide a bunker which carries its load of ice in the upper region of the car, where it has the greatest cooling effect. Another object is to provide a bunker which can be easily and quickly changed from ice holding to collapsed position, and whose parts, in either position, are of sufficient strength to withstand rough usage without requiring frequent repair.

Top icing has recently come into extensive use in the shipment of certain products, especially fresh vegetables. Under this system, ice in cracked or small lump form is scattered throughout the load, and when loading is completed, additional cracked ice is placed in a layer on top of the load. This layer of top ice is ordinarily blown into the car through a hose by compressed air, the operator standing in the transverse center aisle and blowing the ice over the load all the way to the ends of the car. My invention is particularly useful in such service, because when the bunkers are collapsed, the entire interior of the car can be used for lading, and there are no obstructions depending from the ceiling to interfere with the blowing in of the top icing. The same car can be used for standard icing service with the ice in the bunkers at the ends of the car, and for either top icing service or unrefrigerated freight service with the bunkers collapsed and the full length of the car available for lading. All movable parts of the ice bunkers are attached and carried in the car at all times, so that the change from bunker service to full load service and vice versa can be made without special equipment and without

laying the car up. Thus the car can be used for one class of service on its outward trip and for another class of service on its return trip.

These and other objects and advantages of the invention will be made more apparent by the following description, which should be read with the understanding that changes, within the scope of the claims hereto appended, may be made in the form, construction and arrangement of the several parts herein shown and described, without departing from the spirit of the invention.

A preferred embodiment of the invention will now be described with reference to the accompanying drawings, wherein

Fig. 1 is a longitudinal vertical section, taken on the line 1—1 of Fig. 2, of the end portion of a refrigerator car showing my improved ice bunker in ice holding position.

Fig. 2 is a broken transverse section taken on the line 2—2 of Fig. 1.

Fig. 3 is a broken transverse section taken on the line 3—3 of Fig. 1.

Fig. 4 is a longitudinal section, taken on the line 4—4 of Fig. 5, showing the bunker in collapsed position.

Fig. 5 is a broken transverse section taken on the line 5—5 of Fig. 4.

Fig. 6 is a part sectional side elevation, enlarged, of the locking means, shown in broken lines at the upper right of Fig. 2, for holding the bunker side plates in folded position.

Fig. 7 is a part sectional end elevation of the same.

Fig. 8 is a side elevation, enlarged, of one of the guide tracks from which the bulkhead is suspended.

Fig. 9 is a transverse section of the same, showing the mounting of the bulkhead thereon.

In the drawings, the reference numeral 11 designates the floor of a refrigerator car, 12 is its end wall, 13 is one of its side walls, 14 is the outer roof, 15 is the inner roof or ceiling, 16 is one of the hatches for loading ice into the bunker, and 17 is the floor rack or false floor on which the lading is carried. These parts are all common in the art, and their particular construction is not material to the present invention.

My ice bunkers are positioned at the ends of the car, and extend across its full width. Each bunker comprises an ice supporting grate and four vertical walls, all except one of which are movable to positions adjacent the floor, ceiling, and end wall of the car.

The ice grate 18 is hinged at 19 to fixed brack-

ets 20 secured to the end wall 12. When in ice holding position, the grate is preferably horizontal, and is positioned a considerable distance above the floor 11, as shown in Fig. 1. This position supports the ice in the upper portion of the car, and leaves a large open air space below, which materially improves air circulation and cooling effect. It also permits the grate to swing down to vertical position against the end wall 11 when the bunker is collapsed, as shown in Fig. 4. The ice grate is preferably formed of a series of parallel spaced inverted channel members, perforated as shown, mounted upon longitudinal angle bar 21, and for convenience in handling, is made in three sections as shown in Figs. 3 and 5. However, any suitable construction of said grate may be used.

The forward edge of the grate 18 is supported in horizontal position, Figs. 1 and 2, by a vertical bulkhead 22 which is hinged at 23 to brackets 24 secured to the floor 11. This bulkhead is preferably, but not necessarily, formed of perforated ply-wood supported by angle bars 25, and for convenience may be made in three sections, as shown in Fig. 2. The grate angle bars 21 are provided with notches, one of which is shown at 26 in Fig. 1, which interlock with studs 27 projecting from the angle bars 25 of the bulkhead sections 22, thereby holding the bulkhead sections vertical and the grate sections horizontal.

When the bunker is collapsed, the bulkhead sections 22 fold down upon the floor, as shown in Figs. 4 and 5, and form a continuation of the floor rack 17 at the same level as said rack. The grate 18 folds down to vertical position and forms a lining for the end wall 12, keeping the lading away from said end wall to allow air to circulate around it. The notches 26 and studs 27 interlock again in this position, as shown in Fig. 4.

40 The walls of the ice bunker extend from the grate 18 upwardly to the ceiling of the car. The rear wall 28, Figs. 1 and 3, is formed as a screen or other suitable member, and is mounted in fixed position adjacent the end wall 12 of the car by suitable vertical spacers 29. The side walls 30 are preferably formed of metal plates, provided with ventilating louvers 31, and reinforced by vertical channel members 32. The reinforcing channels at the edges of the plates 30 may be integral therewith, as shown. The plates 30 are hingedly hung from horizontal rods 33 secured to the side walls 13 by brackets 34.

Each plate 30 has a movable extension 35 at its lower end, said extension being formed of a perforated metal plate having its upper edge bent back upon itself to make a loop 36, Figs. 1 and 3. A horizontal rod 37 extends through said loop and through ears 38 secured to the reinforcing channels 32 of the plate 30, and said channels are carried down below the lower edge of said plate 30 as shown at 32a.

When the bunker is in ice holding position, the side plate 30 hangs vertically as shown in Fig. 3, and is spaced from the side wall 13 by the channels 32. The extension 35 also hangs vertically, and its lower edge fits into a groove 39 formed along the edge of the grate. The hinge connection formed by the rod 37, and the bearing of the extended lower ends 32a of the channels 32 against the back of the extension 35, prevents the plate 30 from swinging outwardly into the bunker. However, when the extension is first lifted bodily enough to clear the groove 39 of the grate, it can be swung up about the rod 37 to a vertical position against the plate 30, and said

plate then can be swung up about its hinge rod 33 to a horizontal position beneath the ceiling of the car, as shown in Figs. 4 and 5.

Locking means are provided for holding the side plates 30 in horizontal position beneath the ceiling. As an example of such locking means, I have shown, in Figs. 2, 6 and 7, a bracket 40 depending from the ceiling at the center of the car, and a pair of locking pins 41 extending through said bracket. Each pin has a short right angle bend 42 at its forward end and a longer return bend 43 at its rear end. The bracket 40 has spaced flanges 44 provided with slots 45 through which the pins 41 extend. The ends 32a of the channels at the forward edges of the plates 30 rest upon said pins 41, as shown in Fig. 7. To release said plates, the pins 41 are turned so that their ends 42 are in line with the slots 45 in the bracket, and are then withdrawn rearwardly to free the channel ends 32a.

The ceiling 15 of the car is raised a few inches above the ice bunker to form a recess 46, Figs. 1 and 4, so that the side plates 30, when raised to horizontal position, are housed within said recess, and do not project below the level of the ceiling. A reinforcing bar 47 of reversed angle section extends across the ceiling at the forward edge of the recess 46.

The front or bulkhead wall 48 of the bunker is suspended from tracks at the sides of the car, and slides rearwardly when the bunker is collapsed. The tracks 49, Figs. 1, 2, 8 and 9, one at each side, are secured to the side walls 13 near the ceiling, and are formed as channels upon which rollers 50 may travel. The brackets 34, in which the hinge rods 33 of the plates 30 are mounted, are formed as ears extending upwardly from said tracks.

The bulkhead wall 48 is preferably, but not necessarily, formed as a perforated metal plate, Figs. 1 and 2, stiffened by vertical channel bars 51, a horizontal channel bar 52 across its top, and a horizontal angle bar 52a across its bottom. It extends down almost to the level of the ice grate 18. A solid wooden pad 53 is fastened to the front faces of the channel bars 51, the upper edge of said pad being spaced below the ceiling. A section of screen 54 may extend from the top of said pad upwardly to the top of the bulkhead. The rollers 50 are mounted on the side channel bars 51.

The bulkhead 48 is held in forward position at the top by swinging brackets 55, Figs. 1, 2 and 4, which hang down from pivots 56 secured to the ceiling reinforcing bar 47. The lower ends of said brackets 55 are forked to fit over the channel bar 52 at the top of the bulkhead, and have bolts 57 which pass through said channel bar. The bottom of the bulkhead 48 is held from swinging forwardly by overlapping behind the channel bars 52 of the lower bulkhead 22, as shown at 58 in Fig. 1, and is prevented from moving rearwardly by swinging latches 59, Figs. 1 and 5, which drop through slots in the angle bar 52a and engage the edge of the front bar of the grate 18.

When the bunker is in ice holding position, as shown in Fig. 1, the pad 53 of the upper bulkhead section is in vertical alignment with the lower bulkhead section 22, so that the two sections form a continuous bulkhead across the end of the lading compartment of the car. Said bulkhead is rigidly secured to resist end thrust of the lading by the swing brackets 55 at the top, by the hinges 23 at the bottom, and by being braced to the end wall of the car by the grate bars 21.

at the center where the two sections meet. Free movement of air from the upper portion of the lading compartment to the ice bunker is permitted by the screened open space above the bulkhead pad 53 and said air passes downwardly through the bunker and the grate 18, and through the spaces between the lining members 28 and 30 and the walls of the car, into the open space beneath said grate, from which it returns to the lower portion of the lading compartment through the perforated lower bulkhead 22 and beneath the same into the space below the floor rack 17.

To collapse the ice bunker, the bolts 57 connecting the top of the upper bulkhead 48 with its locking brackets 55 are first removed. The extensions 35 of the side plates 30 are lifted and swung up against said plates, and said plates are then swung up to their horizontal positions within the ceiling recess 46 and locked by the pins 41. Next the latches 59 at the bottom of the upper bulkhead 48 are disengaged from the grate 18, the swinging brackets 55 are disengaged from the top of said bulkhead, and said bulkhead is shifted bodily toward the end wall, rolling on its suspending tracks 49. In this position, the top of the upper bulkhead 48 supports the rear edges of the horizontal side plates 30, as shown in Fig. 4. After said upper bulkhead has been moved back, the grate sections 18 are lifted enough to disengage the lower bulkhead sections 22, which are then dropped to horizontal position on the floor. Finally the grate sections 18 are swung down to vertical positions adjacent the end wall.

It will be seen from Fig. 4 that when the ice bunker is collapsed, the upper bulkhead 48 and the grate 18 are in vertical alignment adjacent the end wall of the car, and provide a lining to keep the lading spaced from said end wall to permit air circulation. It will also be seen that the floor rack 17 is extended by the folded lower bulkhead 22, so that the false or lading floor is continuous and level to the end of the car. From Figs. 4 and 5, moreover, it will be seen that, when the bunker is collapsed, there are no projections from the side walls of the car except the tracks 49, which are near the ceiling and therefore do not interfere with the lading; that there are no parts hanging below the level of the ceiling 15 except the swinging brackets 55, which are so small that they do not interfere in any way with either the lading or the top icing thereof; and that the hatches 16 are effectively screened by the louvered side plates 30, so that there can be no pilfering of the car through said hatches, and so that said hatches can be left open for ventilation if desired. It is to be noted, furthermore, that all parts of the bunker are in use and are attached to the car in both positions, so that none of said parts can be misplaced or lost.

I claim:

1. In a refrigerator car having an ice bunker at one end, a transverse bulkhead separating said ice bunker from the remainder of the car, said bulkhead having an upper section movable to a position parallel with and adjacent to the end wall of the car and a lower section movable to a substantially horizontal position adjacent the floor, and an ice supporting grate in said bunker, said grate being movable to a position adjacent said end wall in vertical alignment with the moved upper bulkhead section.

2. In a refrigerator car having an ice bunker at one end, a lading compartment, and a false

floor in said lading compartment raised above the main floor, a transverse bulkhead separating said ice bunker from said lading compartment, said bulkhead having a lower section movable to a position in horizontal alignment with said false floor, an ice supporting grate in said bunker, one edge of said grate being supported by said lower bulkhead section when the latter is in bulkhead forming position, and said grate being movable to a substantially vertical position adjacent the end wall of the car at the end of said lower bulkhead section when the latter is in horizontal position.

3. In a refrigerator car having an ice bunker at one end, a lading compartment, and a false floor in said lading compartment raised above the main floor, a transverse bulkhead separating said ice bunker from said lading compartment, said bulkhead having an upper section movable to a position parallel with and adjacent the end wall of the car and a lower section movable to a position in horizontal alignment with said false floor, and an ice supporting grate in said bunker movable to a position adjacent said end wall in vertical alignment with the moved upper bulkhead section.

4. In a refrigerator car having a collapsible ice bunker at one end, a transverse bulkhead separating said ice bunker from the remainder of the car, the bottom of said bulkhead being spaced from the floor of the car and said bulkhead being movable to a vertical position in adjacent spaced relation with the end wall of the car, and an ice supporting grate in said bunker, said grate being movable to a vertical position in adjacent spaced relation with said end wall between the bottom of the moved bulkhead and the floor of the car, said bulkhead and said grate when in said moved positions forming a lining adjacent said end wall and spaced therefrom to permit air circulation.

5. In a refrigerator car having an ice bunker at one end, a lading compartment, and a false floor in said lading compartment raised above the main floor to provide an air space beneath the lading, a transverse bulkhead separating said ice bunker from said lading compartment, said bulkhead being movable to a horizontal position spaced above the floor at the end of said false floor to form a continuation of said false floor extending to the end of the car, and to provide a continuation of said air space beneath the lading on said false floor.

6. In a refrigerator car having an ice bunker at one end, a transverse bulkhead separating said ice bunker from the remainder of the car, said bulkhead being divided into upper and lower sections, both of said sections being movable away from their bulkhead forming positions, a movable ice supporting grate having one edge connected with the end of the car and its other edge connected with and supported by said lower bulkhead section, and means for separably securing the lower edge of said upper bulkhead section at the junction of said grate with said lower bulkhead section.

7. In a refrigerator car having a collapsible ice bunker at one end, a transverse bulkhead separating said ice bunker from the remainder of the car, said bulkhead being movable toward the end of the car to collapse said bunker, and a movable bracket pivotally connected with ceiling of the car and having a forked lower end engaging the upper edge of said bulkhead when in bunker forming position to prevent movement thereof away from said position.

8. In a refrigerator car having side walls and a roof with ice hatches therein, a collapsible ice bunker in the car beneath said hatches, lining members forming the sides of said bunker parallel with and adjacent the side walls of the car, said lining members being movable away from said side walls to substantially horizontal positions beneath said hatches to form pilfer-proof closures therefor when the bunker is collapsed, and said side walls being free from projections when said lining members are moved away therefrom.
9. In a refrigerator car having walls and a roof with an ice hatch therein, lining members spaced from said walls and forming portions of a collapsible ice bunker beneath said hatch, said lining members having air apertures therein and the spaces between said lining members and said walls forming channels for the circulation of air around said bunker, and one of said lining members being movable to a substantially horizontal position below said hatch to form a ventilating pilfer-proof closure therefor when the ice bunker is collapsed.
10. In a refrigerator car having walls and a roof with an ice hatch therein, a collapsible ice bunker within the car beneath said hatch comprising a movable bulkhead extending across the car and lining members adjacent the end and side walls of the car, one of said lining members being movable to a substantially horizontal position beneath said hatch to form a closure therefor, and said bulkhead being movable to a position beneath said horizontal hatch closing member to lock it in said horizontal position.
11. In a refrigerator car having walls and a roof with an ice hatch therein, a collapsible ice bunker within the car beneath said hatch comprising a movable bulkhead extending across the car and lining members adjacent the end and side walls of the car, the lining members adjacent the side walls being hingedly mounted to swing upwardly to horizontal positions beneath said hatch to form a pilfer-proof closure therefor, and locking means for holding said members in said horizontal position, said locking means being inaccessible from outside the car through said hatch when the ice bunker is collapsed.
12. In a refrigerator car having walls, a roof with an ice hatch therein, and an ice bunker beneath said hatch, an ice grate in said bunker, a lining member for one wall of said bunker, said member being hingedly mounted at its upper end to swing upwardly to substantially horizontal position beneath said hatch, an extension movably secured to the lower end of said member, the bottom of said extension normally engaging one edge of said grate to prevent swinging movement of said member, and said extension being freed from engagement with said grate by its movement relative to said member.
13. A collapsible ice bunker comprising an ice supporting grate and substantially vertical wall members, one of said wall members being hingedly mounted at its upper end to swing upwardly, an extension hingedly connected with the lower end of said member, the last mentioned hinge connection permitting vertical movement of said extension relative to said member, the bottom of said extension normally engaging one edge of said grate to prevent swinging movement of said member, and said extension being freed from engagement with said grate by its movement relative to said member.
14. In a refrigerator car having a ceiling, said ceiling having a raised portion forming a recess adjacent one end of the car, movable members forming a collapsible ice bunker in the end of the car beneath said recess, some of said members being movable to horizontal positions within said recess when said bunker is collapsed, whereby the full interior height of the car is maintained throughout its length when the ice bunker is collapsed.
15. In a refrigerator car having a collapsible ice bunker at one end, an ice supporting grate in said bunker, said grate being hinged to a wall of the car to swing downwardly to a vertical position against said wall, a vertical bulkhead section resting upon the floor of the car and extending upwardly to and terminating at said grate, the free edge of said grate being supported by said bulkhead section, and said bulkhead section being movable to a horizontal position upon the floor of the car.

GUSTAV P. TORBURN.
